UNITED STATES PATENT OFFICE.

BURTON H. GEDGE, OF ANDERSON, INDIANA, AND BURTON H. GEDGE, JR., OF CLEVELAND, OHIO.

REEL.

1,162,472.

Specification of Letters Patent.

Patented Nov. 30, 1915.

Application filed February 5, 1913. Serial No. 746,255.

To all whom it may concern:

Be it known that we, BURTON H. GEDGE and BURTON H. GEDGE, Jr., citizens of the United States, residing at Anderson, in the 5 county of Madison and State of Indiana, and at Cleveland, in the county of Cuyahoga and State of Ohio, respectively, have invented a new and useful Reel, of which the following is a specification.

Our invention relates to reels, as for 10 strips, wires, rods, and other metal members. Its object is to provide a magnetic reel, whereby the hooked ends ordinarily necessary for starting the winding operation may be eliminated, and automatically 15 to set the reel in motion at the beginning of the supply of the wire or strip to be wound, and automatically to stop the reel and remove it from the coil at the completion 20 of the winding operation.

The accompanying drawings illustrate our invention.

Figure 1 is a semi-diagrammatic view 25 illustrating our invention as applied in connection with a rolling mill; Fig. 2 is a plan view of the reel, substantially on the line 2—2 of Fig. 1; and Fig. 3 is a section on the line 3—3 of Fig. 2.

The rolling mill 10 operates on the strip 30 or wire 11, here illustrated as a strip, to form it as desired, this strip as it passes from the rolling mill being turned up on edge to pass into a slotted guide 12, from which it passes around the post 13 to the 35 reel 14. This reel is hung from the lower end of a shaft 15 rotatably mounted in a frame 16, the upper end of such shaft being connected by a swivel 17 and a link 18 to a lever 19, which may be operated to raise 40 the reel by suitable means, here shown as a solenoid 20 and its core 21. The core 21 and the counter-weight 22 partly counter-balance the weight of the reel 14, so that when the solenoid is energized the reel 14 45 is lifted to the dotted line position while when it is deenergized the reel drops to the full line position.

The reel 14 comprises a base-plate 30 50 preferably of non-magnetic material, projecting upward from near the center of which is a tube 31 of magnetic material, concentric with the shaft 15. A plurality of electro-magnet windings 32 are arranged around the periphery of the tube 31, and 55 extend radially outward therefrom, these

windings conveniently being so connected that alternate poles have their outer ends of opposite polarity. These windings are inter-connected in any suitable manner, and are energized through wires 33 leading upward axially through the shaft 15 to slip rings 34 around the edges of which slidingly fit brushes 35 vertically slidable in the frame 16 so as to remain always in contact with the slip rings whatever the position of the shaft 15 and the reel. Within each winding 32 is slidably mounted a core 36, to the outer end of which is fixed a circular cylindrical segment 37 of which the lower edge is conically beveled internally at 38, both the cores and the segments being of magnetic material. The segments 37 are sufficiently short circumferentially so that spaces are left between adjacent segments, and are of sufficient axial extent to furnish 60 the desired winding surface for the reel. The cores 36 and segments 37 are movable axially within the windings 32, being drawn inwardly by springs 39 and by the solenoid action of the windings, and being guided in 65 their movements by a ring 40 of non-magnetic material through which the cores 36 and bolts 41 on the circumferential ends of the segments 37 project. The bolts 41 are 70 preferably provided with nuts 42 on their inner ends, for limiting the outward movement of the cores and segments.

Beneath the reel is a driving plate 43 having the upper part of its periphery conically beveled at 44 to correspond to the beveled 75 portions 38 of the segments 37, so that when the reel 14 is dropped upon the driving plate the beveled portions 44 and 38 cooperate to force the segments 37 and cores 36 outwardly to the dotted line position 80 shown in Fig. 3. The driving plate 43 is mounted on the upper end of a vertical driving shaft 45 in alinement with the shaft 15, such driving shaft 45 being suitably rotated 85 from any convenient source of power, as 90 through a belt 46 and a worm gearing 47.

Suitably mounted above the guide 12 is a switch-carrying bar 50, vertically adjustable by screws 51. Mounted on the bar 50 are three switches 52, 53, and 54 respectively, 95 which switches are biased by springs 55 to closed, open, and closed positions respectively and are provided with operating arms 56, 57, and 58 which depend into the slot into 100 the guide 12 and slidingly engage the top of 110

the strip 11 so as to move their respective associated switches to open, closed and open positions when such guide is occupied by the strip. The switches 52 and 54 are connected in series in the circuit 59 of the solenoid 20, and the switch 53 is connected in a circuit 60 leading through the brushes 35, slip rings 34, and wires 33 to the windings 32 of the reel, the two circuits being supplied 10 in common through a switch 61 from a suitable source of electro-motive force 62.

Assume that the strip 11 is about to be supplied through the rolling mill 10, the slot in the guide 12 being empty. As a result of the emptiness of the guide 12, the switch 53 is open and the switches 52 and 54 are closed. If the switch 61 is closed at this time, as it is continuously during winding operations, the solenoid 20 will be energized 20 by reason of the closed position occupied by the switches 52 and 54, and in consequence the reel 14 will be in its raised position, as shown in dotted lines in Fig. 1. The winding of the reel is deenergized at this time, 25 because the switch 53 is open. As the strip 11 is now supplied through the rolling mill 10 and feeds into the guide 12, its upper edge successively engages the depending arms 56, 57, and 58, moving them from their 30 dotted line to their full line positions. This movement of the arm 56 opens the switch 52 to break the circuit 59, thereby deenergizing the solenoid 20 and causing the reel 14 to drop from its dotted line to its full 35 line position. The dropping of the reel causes segments 37 to be forced outward by the engagement of the beveled portions 38 and 44. The movement of the arm 57 closes the switch 53 to complete the circuit 60. This 40 causes the energization of the windings 32 of the reel 14, so that the magnetic pull of such windings assist the springs 39 to pull the cores 36 inward. The plate 43 already 45 being in rotation, driven from the belt 46, the engagement of the lower edges of the segments 37 with such plate, at least after the energization of the winding 32, caused the reel to rotate with the plate. The movement of the arm 58 opens the switch 54, but 50 this produces no effect at this time.

After passing the three arms 56, 57, and 58, the strip 11 now passes into contact with the reel where it is grasped by the magnetic attraction due to the windings 32 and is carried around with the reel, being guided by the post 13. This winding action continues, and forms a continually growing coil of the strip 11 while the supply of the latter continues. As the rear end of the strip 11 passes 60 from the rolling mill 10 and the guide 12, it first releases the arm 56 to allow the closing of the switch 52, but this produces no effect at this time. It next releases the arm 57 to cause the opening of the switch 53, thereby 65 deenergizing the windings 32 and thus mag-

netically releasing the reel from the coil wound upon it. However, the reel, by reason of its momentum and of the spring clamping action of the springs 39 between the segments 37 and the edge of the plate 70 44, still continues in rotation until the last of the coil is wound. The passing of the lower end of the strip 11 from the guide 12 finally releases the arm 58 to allow the closing of the switch 54, which now completes 75 the circuit 59. This causes the energization of the solenoid 20, which draws down its core 21 to lift the reel 14 from its full line to its dotted line position, or out of the coil wound upon it, the spring 39 drawing the 80 segments inward as the reel is raised and thus facilitating its removal from the coil. The completed coil may now be taken away, and a second length of strip 11 fed to and through the rolling mill 10, which may be 85 the last of a series of rolls, whereupon the action above described is repeated.

The switches 52, 53, and 54 are located as they are so as to cause the energization of the solenoid 20 only when one length of the 90 strip 11 has passed completely out of the guide 12 and before another length of such strip has been supplied thereto, and to energize the windings 32 immediately after the reel has been dropped to its full line position 95 and to deenergize it immediately before it is raised to its dotted line position. The screws 51 provide means for adjusting the switch bar 50 and the switches 52, 53, and 54 vertically according to the width of the 100 strip 11 being wound.

We claim as our invention:

1. In combination, a magnetic reel for winding material, and means controlled by the passage of such material to the reel for controlling the energization thereof and the movement thereof into and from position to receive the material.

2. In combination, a magnetic reel for winding material and means controlled by the passage of such material to the reel for controlling the energization thereof and a driving disk adapted to be gripped by the reel to produce rotation of the reel.

3. In combination, a magnetic reel, a 115 guide through which material is supplied to said reel to be wound thereon, a switch controlled by the passage of said material through said guide, and electro-magnetic means controlled by said switch for controlling the movement of said reel either into and out of place to receive such material from said guide.

4. In combination, a reel, having a vertical axis and an unobstructed end, and an 125 electro-magnetic winding mounted in said reel for making its periphery magnetic so that it will grip magnetically any proper material supplied to it.

5. In combination, a reel rotatable about 130

5 a vertical axis, a platform associated with said reel and toward and from which said reel may be axially shifted to leave the reeled material upon said platform free from the reel, and means controlled by the supply of material to said reel for causing said reel to be shifted axially.

10 6. In combination, a reel rotatable about and movable along an axis, a rotary driving member into and out of clutching engagement with which the reel is moved when moved along its axis, and means independent of the clutch for supporting said reel for movement along its axis toward and 15 from the clutch whereby the reeled material may be withdrawn laterally from between the reel and clutch.

20 7. In combination, a reel, the periphery of said reel being composed of a plurality of radially movable segments, electro-magnetic windings for drawing said segments radially inward, and means for forcing said segments outward.

25 8. In combination, a reel, the periphery of said reel being composed of a plurality of radially movable segments, electro-magnetic windings for drawing said segments radially inward, and a co-axial rotary driving plate, said driving plate and said reel 30 being relatively movable axially to produce engagement and disengagement between the driving plate and the peripheral segments of the reel.

35 9. In combination, a reel, the periphery of said reel being composed of a plurality of radially movable segments, electro-magnetic windings for drawing said segments inward, a rotary driving plate, said driving plate and said reel being relatively movable axially to produce engagement and disengagement 40 between the driving plate and the peripheral segments of the reel, and means controlled by the supply of material to said reel for controlling said relative axial movement.

45 10. In combination, a reel, the periphery of said reel being composed of a plurality of

radially movable segments, electro-magnetic windings for drawing said segments radially inward, a rotary driving plate, said 50 driving plate and said reel being relatively movable axially to produce engagement and disengagement between the driving plate and the peripheral segments of the reel, and means controlled by the supply of material 55 to said reel for controlling the energization of said windings.

11. In combination, a reel, the periphery of said reel being composed of a plurality of radially movable segments, electro-magnetic 60 windings for drawing said segments radially inward, a rotary driving plate with the edge of which the peripheral segments of the reel may be made to engage, and springs assisting said windings to draw said 65 segments radially inward.

12. In combination, a reel, the periphery of said reel being composed of a plurality of radially movable segments, electro-magnetic windings for drawing said segments 70 radially inward, a rotary driving plate with the edge of which the peripheral segments of the reel may be made to engage.

13. In combination, a reel, the periphery of said reel being composed of a plurality 75 of radially movable segments for drawing said segments radially inward, and means for forcing said segments outward.

In witness whereof, we have hereunto set our hands at Indianapolis, Indiana, this 80 29th day of January, A. D. one thousand nine hundred and thirteen, and at Cleveland, Ohio, this 31st day of January, A. D. one thousand nine hundred and thirteen, respectively.
